UNITED STATES PATENT OFFICE.

EDWARD C. MEIER, OF PHOENIXVILLE, PENNSYLVANIA.

HEADER.

1,154,194.

Specification of Letters Patent. Patented Sept. 21, 1915.

Application filed May 27, 1915. Serial No. 30,759.

To all whom it may concern:

Be it known that I, EDWARD C. MEIER, a citizen of the United States, residing at Phoenixville, in the county of Chester and 5 State of Pennsylvania, have invented certain new and useful Improvements in Headers, of which the following is a specification.

My invention relates to improvements in headers, and more particularly to a header 10 designed for use as a part of a superheater or preheater for steam boilers, and the object of the invention is to provide an improved construction of header which can be made of sheet steel or other similar material, 15 and which dispenses with the necessity for bolts and rivets to hold the parts together.

A further object is to improve upon the construction illustrated in my application for patent filed March 29, 1915, and given 20 Serial No. 17,767.

With these and other objects in view, the invention consists in certain novel features of construction and combinations and arrangements of parts as will be more fully 25 hereinafter described and pointed out in the claims.

In the accompanying drawings: Figure 1 is a broken view in longitudinal section illustrating my improved header. Fig. 2 is a 30 view in transverse section on the line 2—2 of Fig. 1. Fig. 3 is a view in transverse section on the line 3—3 of Fig. 1. Fig. 4 is a view on a reduced scale similar to Fig. 2 illustrating a modification. Figs. 5 and 6 35 are views similar to Figs. 1 and 2 illustrating a modification in which a plurality of tubes are supported in alinement in a single head, and Fig. 7 is a view similar to Figs. 2 and 6 illustrating another modification.

1 and 2 represent the sheets of the boiler water leg connected by a stay tube 3, and 40 while I have illustrated my improvements in connection with a stay tube, it is of course to be understood that the device may be 45 located at any point where the necessary heat may be had.

4 represents my improved header which 50 comprises two main sections which, to distinguish them, I shall refer to as "inner" and "outer" sections. To the outer section I have applied the reference numeral 5, and to the inner section the reference numeral 6. In the preferred form of my invention as 55 shown in Figs. 1, 2, and 3, the sections 5 and 6 are cylindrical or circular in cross section,

but I do not limit myself to this particular shape, and have illustrated in Fig. 4 as a modification, the parts in rectangular or angular formation, and may so shape the header or use any other shape desired. The 60 outer section 5 is appreciably larger in diameter than the inner section 6, and each section is formed of a single metal sheet, the intermediate portions of the respective sheets constituting the ends of the header, while 65 the edges of the respective sections are joined as will be hereinafter described. In section 6, I locate a ring 7 which constitutes a reinforcement and a threaded opening 8 is formed in the section 6 and ring 7 to receive the threaded end of a pipe 9. A ring 10 is located inside of section 5, and said ring and section are formed with a screw-threaded opening 11 to receive the threaded end of a pipe 12. In assembling the two 70 sections, the edge of section 6 is flared outwardly as shown at 13, while the edge of section 5 is straight as indicated in dotted lines in Fig. 1. Section 6 is then positioned inside of section 5 with the edges of section 6 75 bearing directly against the ring 10, and while in this position the edge of section 5 is bent inwardly as shown at 14 so as to fit snugly against the outwardly bent portion 13 of section 6. A ring 15 is secured within 80 the outwardly bent portion 13 of section 6 and bears directly against the edge of ring 7, and as indicated in the drawings, I join all of the parts wherever possible by welding. These welding points I have indicated 85 by the reference numeral 16, so that the parts are permanently connected and rendered steam and water tight. It will thus be noted that the header is formed without rivets or bolts, and the parts are rigidly 90 secured together.

A removable plate 17 is secured to the ring 15 by screws 18 which project through perforated ears 19 on the plate and are screwed into threaded openings 20 in the 100 ring. The intermediate portion of the plate is conical as shown at 21 so as to readily guide the same into proper position in the ring, and this plate 21 is provided with a central opening 22 in which a tube 23 is 105 secured. The inner section 6 is provided with a central opening 24 in which a tube 25 is secured. The tube 25 projects beyond the end of tube 23, and is closed at its inner end as shown at 26, while the end of tube 110

23 is open allowing a free circulation of water and steam through the header and between the tubes as will be readily understood. The outer end of section 5 is formed with a relatively large opening 27 conforming in shape and slightly larger than the plate 17 so as to permit the plate 17 with its tube 23 to be removed through the header and also permit the screws 18 to be easily adjusted as occasion may require. The plate 28 closes the opening 27 and fits snugly within the same, said plate having a bolt 29 projecting outside of the header and through a yoke 30 to securely clamp the plate inside the header.

15 In the modification shown in Fig. 4, the parts are of general rectangular shape, but in other respects the construction is like that above described, and I have used the same reference numerals to indicate like parts.

20 In the modification illustrated in Figs. 5 and 6, the header is elongated or oblong shape, and the plate 31 corresponding to plate 17 of the form above described is oblong or elongated to accommodate a number of tubes 23 which project into outer tubes 25, and in this modification, as in the other, I have used the same reference numerals to indicate like parts.

25 In the modification illustrated in Fig. 7, a plurality of tubes 23 are supported in a circular plate 17, but in other respects the construction is precisely like that above described.

30 It will therefore be noted that my improved construction of header may be utilized in connection with one or more series of tubes arranged in any approved manner, and the invention is not limited to any particular arrangement of tubes, but is broadly to the construction of header in connection with any construction of tubes which is practicable.

35 Various other slight changes might be made in the general form and arrangement of parts described without departing from my invention, and hence I do not limit myself to the precise details set forth, but consider myself at liberty to make such changes and alterations as fairly fall within the spirit and scope of the appended claims.

Having thus described my invention, what I claim as new and desire to secure by Letters Patent is:

40 1. A header, comprising two sections, each section composed of a single metal sheet, the intermediate portions of the respective sheets constituting the ends of the header, one section smaller than the other, the smaller section fitting within the larger section and secured thereto, and a ring fitting within the larger section and against which the edge of the smaller section bears, substantially as described.

45 2. A header, comprising two sections, each section composed of a single metal sheet, the intermediate portions of the respective sheets constituting the ends of the header, one section smaller than the other, the smaller section having its edge flared outwardly and located inside of the larger section, the larger section having its edge bent inwardly upon the outwardly bent edge of the smaller section, substantially as described.

50 3. A header, comprising two sections, each section composed of a single metal sheet, the intermediate portions of the respective sheets constituting the ends of the header, one section smaller than the other, the smaller section having its edge flared outwardly and located inside of the larger section, the larger section having its edge bent inwardly upon the outwardly bent edge of the smaller section, and a ring fitting within the larger section and against which the edge of the smaller section bears, substantially as described.

55 4. A header, comprising two sections, each section composed of a single metal sheet, the intermediate portions of the respective sheets constituting the ends of the header, one section smaller than the other, the smaller section having its edge flared outwardly and located inside of the larger section, the larger section having its edge bent inwardly upon the outwardly bent edge of the smaller section, a ring secured in the outwardly flared portion of the smaller section, 100 a plate removably secured to said ring, said plate having a central opening therein, and an open ended tube secured in said plate, said smaller section having an opening therein, and a tube secured in said last-mentioned opening, said last-mentioned tube inclosing the first-mentioned tube, extending beyond the first-mentioned tube and having a closed end, substantially as described.

60 5. A header, comprising two sections, each section composed of a single metal sheet, the intermediate portions of the respective sheets constituting the ends of the header, one section smaller than the other, the smaller section having its edge flared outwardly and located inside of the larger section, the larger section having its edge bent inwardly upon the outwardly bent edge of the smaller section, a ring fitting within the larger section and against which the edge of the smaller section bears, a ring secured in the outwardly flared portion of the smaller section, a plate removably secured to said ring, said plate having a central opening therein, and an open ended tube secured in said plate, said smaller section having an opening therein, and a tube secured in said last-mentioned opening, said last-mentioned tube inclosing the first-mentioned tube, extending beyond the first-men- 120 125 130

tioned tube and having a closed end, substantially as described.

6. A header comprising two sections, each section composed of a single metal sheet, the intermediate portions of the respective sheets constituting the ends of the header, the edges of said sections overlapping and welded together, rings in both sections fitting the inner faces thereof, said rings and sections having threaded openings, threaded pipes projecting into the threaded openings, the end of the smaller section supporting a pipe, a removable plate secured between the sections and supporting an inner pipe, said outer section having an opening therein, and means closing said opening, substantially as described.

7. A header of the character described having a ring secured within the same, a removable plate having perforated ears at its edges, screws located in said perforated ears and screwed into the ring, tubes supported by the header and plate respectively, said

header having an opening in its outer end conforming in shape to the shape of the 25 plate, and means normally closing said last-mentioned opening, substantially as described.

8. A header, comprising two sections, each section composed of a single metal sheet, the intermediate portions of the respective sheets constituting the ends of the header, the edges of said sections overlapping and secured together, a plurality of tubes projecting from one header section, a removable plate secured in the header, and a plurality of tubes secured in the plate and projecting into the first-mentioned tubes, substantially as described.

In testimony whereof I have signed my 40 name to this specification in the presence of two subscribing witnesses.

EDWARD C. MEIER.
